UNITED STATES PATENT OFFICE.

EGBERT VON LEPEL, OF BERLIN-WILMERSDORF, GERMANY.

CIRCUIT ARRANGEMENT FOR WIRELESS TRANSMITTERS

1,204,720

Specification of Letters Patent.

Patented Nov. 14, 1916.

Application filed February 11, 1914. Serial No. 818,127.

To all whom it may concern:

Be it known that I, EGBERT VON LEPEL, a subject of the King of Prussia, residing at Berlin-Wilmersdorf, in the Empire of Germany, have invented new and useful Improvements in Circuit Arrangements for Wireless Transmitters, of which the following is a specification.

My invention relates to a novel method of producing a low frequency current in a simple and effective manner from a high-frequency current so as to render the latter perceptible in telephonic receivers.

In the accompanying drawing, Figure 1 is a diagram illustrating one of the prior methods for producing low-frequency current from high-frequency current; Fig. 2 a diagram illustrating my novel method for producing low-frequency current from high-frequency current, and Fig. 3 a diagram showing a modification of Fig. 2.

The oscillations produced from continuous current by means of a generator of high frequency constructed according to Poulsen, von Lepel, and others, are, as is well known, entirely, or nearly entirely, continuous so that they are not apt to be received, without artificial means, in a detecting device of a telephonic receiver. An interrupter or a similar arrangement will have to be provided for in the receiver or in the transmitter. A very simple solution for the latter case was proposed by von Lepel and Burstyn in the year 1908. This is the so-called continuous-current tone transmitter which is so constructed that in addition to the high frequency circuit *s c* which includes the generator *g* (Fig. 1) for high frequency oscillations fed from the line *p p*, another parallel circuit of low frequency is established that comprises the parts *g t a*. Each of the two circuits furnishes by discharging through the oscillation generator an alternating current of its specific periodicity. When both circuits are connected with the oscillation gap one obtains the result that the intensity of the high frequency oscillations of the circuit *s c* pulsates in the rhythm of the oscillations of the low frequency circuit *t d*. This latter circuit is generally tuned to a readily perceptible tone frequency, that is to say, a number of vibrations, for instance 1000 per second, which the human ear will perceive as sound. The present invention differs from this scheme by the fact that the low frequency circuit is not connected in

parallel with the oscillation generator and that it can in consequence not be excited for itself. This circuit in this case is shunted to a part of the capacity of the high frequency circuit. For this purpose the battery of condenser of this circuit consists of at least two condensers or two groups of condensers connected in series (*c* and *d* in Fig. 2); to one or to one group of those (*c*) a coil *t* is connected in parallel. This arrangement has the result that the high frequency oscillations of the circuit *c d s* (say 1,000,000 oscillations per second) are decomposed in groups of tone frequency such that they become singing oscillations. The pitch of the note depends on the self-induction of the coil *t* on the one hand and of the resulting capacity of the two condensers on the other hand and may be altered by means of one of these electrical factors by means of a keyboard for instance.

The advantage of this new method consists in the fact that no special condenser is wanted for the circuit of tone frequency. Therefore the apparatus becomes simpler and cheaper.

Fig. 3 shows a scheme of connections in which a condenser *e* is put in series with the coil *t*, but this alteration is of no great importance.

If instead of a continuous current an alternating current of technical low frequency is used as feeding current, the whole of the high frequency energy oscillates also in the rhythm of these very slow oscillations, and on the receiving end a note like that from a shrill pipe is obtained.

It is well known that singing oscillations may be produced by supplying an alternating current of tone frequency to a quenching spark-gap or an arc. In such a case the new scheme may serve to obtain better tones if the tone frequency circuit is tuned to the pitch of the alternator.

For transmitting wireless messages the key *k* may be placed in the feeding current line or in the circuit of the low frequency as illustrated in the drawing.

What I claim is:

1. In a wireless transmitter, a main oscillation circuit of high frequency including a condenser and a coil in series, and an auxiliary oscillation circuit arranged in a shunt which bridges a portion of the condenser capacity of said main circuit, said auxiliary circuit having a low-frequency period of

cillation such as corresponds to sounds audible to the human ear.

2. In a wireless transmitter, a main oscillation circuit of high frequency including a condenser and a coil in series, and an auxiliary oscillation circuit arranged in a shunt which bridges a portion of the condenser capacity of said main circuit, on the side farthest away from the said coil, said auxiliary circuit having a low-frequency period of oscillation such as corresponds to sounds audible to the human ear.

3. In a wireless transmitter, a main oscil-

lation circuit of high frequency including a condenser and a coil in series, and an auxiliary oscillation circuit arranged in a shunt which bridges a portion of the condenser capacity of said main circuit, and includes a coil, said auxiliary circuit having a low-frequency period of oscillation such as corresponds to sounds audible to the human ear. 15 20
